(57) **CLAIM**

The ornamental design for a boat accessory rack, as shown and described.

DESCRIPTION

FIG. 1 is a perspective view of a boat accessory rack according to the present invention;

FIG. 2 is a top plan view of the embodiment of FIG. 1;

FIG. 3 is a front elevation view of the embodiment of FIG. 1;

FIG. 4 is a rear elevation view of the embodiment of FIG. 1;

FIG. 5 is a right side elevation view of the embodiment of FIG. 1;

FIG. 6 is a left side elevation view of the embodiment of FIG. 1; and,

FIG. 7 is a bottom plan view of the embodiment of FIG. 1. The claimed design in FIGS. 1-7 is broken to indicate indefinite length.

In the drawings, the broken lines depict environmental subject matter and form no part of the claimed design.

The boat accessory rack is shown with a symbolic break in its length. The appearance of any portion of the article between the break lines forms no part of the claimed design.
